(57) **CLAIM**

The ornamental design for a cylindrical lighting fixture, as shown and described.

DESCRIPTION

FIG. 1 is a front perspective view of a first embodiment of our design, shown in a first position in which the first embodiment is symmetrical about its longitudinal axis;

FIG. 2 is a side view of the first embodiment in the first position;

FIG. 3 is a bottom view of the first embodiment in the first position;

FIG. 4 is a front perspective view of a second embodiment of our design, shown in a first position in which the first embodiment is symmetrical about its longitudinal axis and broken in two locations to indicate that the lengths of the upper cylinder shape and the lower cylinder shape may vary;

FIG. 5 is a side view of the second embodiment in the first position;

FIG. 6 is a bottom view of the second embodiment in the first position;

FIG. 7 is a front perspective view of the first embodiment, shown in a second position in which the lower cylinder shape is angularly disposed relative to the upper cylinder shape;

FIG. 8 is a back perspective view of the first embodiment in the second position;

FIG. 9 is a front perspective view of the second embodiment, shown in a second position in which the lower cylinder shape is angularly disposed relative to the upper cylinder shape; and,

FIG. 10 is a back perspective view of the second embodiment in the second position.

The broken-line disclosure represents unclaimed environmental structure and portions of the lighting fixture which form no part of the claimed design. The areas between the portions of the cylinder shown broken-away form no part of the claimed design.

1 Claim, 10 Drawing Sheets
